UNITED STATES PATENT OFFICE

JOHN A. SMITMANS, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA

MANIPULATOR

Application filed May 19, 1927. Serial No. 192,769.

This invention relates to manipulators and more particularly to manipulators having tilting fingers and side guards, and to improved operating means therefor.

5 An important object of this invention is the provision of improved operating means for tilting fingers.

Another object is to provide improved tilting finger operating means movable bodily with a side guard.

10 A further object is to provide a manipulator having selectively operable side guards and improved tilting finger operating means associated therewith.

15 Certain other objects and advantages will be hereinafter pointed out with particular reference to the accompanying drawings, illustrating the present preferred embodiments of my invention.

20 In the drawings:

Figure 1 is a top plan view illustrating a manipulator embodying my invention;

25 Figure 2 is a sectional view taken on the line II—II of Figure 1;

Figure 3 is a sectional view taken on the line III—III of Figure 1;

Figure 4 is a detail view of the preferred rack and pinion construction; and

30 Figure 5 is a detail sectional view, to enlarged scale, of the joint connecting the pitman rod and the crank for operating the tilting fingers.

35 Referring to the illustrated embodiment there is shown a manipulator having movable side guards 2—3, and tilting fingers 4 movable laterally with the side guard 2. The side guards 2 and 3 are controlled by a plurality of racks 5 and 6 through a mechanism to be hereinafter described. The usual live roll platform between the side guards 2 and 3, is indicated generally by R.

40 The side guard 2 is preferably comprised of a plurality of spaced members attached to a supporting frame 7. The tilting fingers 4 are preferably disposed between the spaced members of side guards 2 and are adapted to reciprocate vertically while depending from pivotal connections 8 at the ends of levers 9.

45 The levers 9 are keyed to a shaft 10 con-

trolled by the tilting mechanism indicated generally by 11.

The tilting mechanism (Fig. 2) preferably comprises a crank 12 having a pitman 13 connected thereto, the pitman cooperating with a lever 9 through a ball and socket joint 14. The pitman 13 is preferably provided with a forked end (Fig. 5) attached to a trunnion block 15 which is adapted to engage the pin 55 of the crank 12, thus forming a universal connection.

50 From the foregoing, it will be obvious that when the crank is rotated the levers 9 are oscillated about the axis of the shaft 10, thereby resulting in vertical movement of the tilting fingers 4 attached to the outer ends of the levers 9.

The crank 12 is preferably attached to the end of a shaft 16 having a non-circular cross-section, preferably square, the shaft being adapted to slide longitudinally through a gear 17 having an opening corresponding to the contour of the shaft 16. The gear 17 is rotated by a motor 18 stationary on the main frame of the manipulator.

70 The frame 7 carrying the side guard 2 and the tilting fingers 4 together with their associated mechanism is adapted to be moved laterally of the roll bed R by means of racks 5 cooperating with pinions 5^a rotated by shaft S₁, geared to a motor M₁ through suitable reducing gearing, indicated generally by G₁. The racks 5 are attached to the frame 7 by longitudinal members 19. The frame 7 and its associated parts is supported by shoes 20 sliding on a suitable channel bearing member 21. Suitably shaped scale guards 22 overlie the bearing members 21 when the parts are in the position shown 75 in Figure 2 thereby preventing scale from falling through the roll bed R upon the bearing surfaces.

80 The side guard 3 is supported by a frame 23 slidable on bearing members 24. The frame is controlled by longitudinal members which are attached to the racks 6. Movement of the racks 6 is controlled by pinions 6^a which are mounted on a shaft S₂. The shaft S₂ is controlled by a motor M₂.

through suitable gearing indicated generally by G₂.

As shown in Figure 4, the racks 5 and 6 and gears 5^a and 6^a are shrouded so that the weight of the racks is carried by the shrouds. As illustrated, the gear shrouds preferably terminate at the pitch line of the gears and the rack shrouds terminate at the pitch line of the racks. The racks are preferably attached to the longitudinal members 19 and 25 which are guided by bearing pieces 19^a and 25^a attached to obliquely extending members 26, which are attached to the main frame supporting the manipulator mechanism. It will thus be seen that the racks are guided from above and below by the bearing pieces 19^a and 25^a supported by members 26, and by the shrouded gears 5^a and 6^a.

The longitudinal members 25 may be provided with scale guards 27 which overlie the bearing members 24. It will be observed that the bearing surfaces 24 are always protected from scale by longitudinal members 25 inasmuch as the material handled lies between the side guards. On the other hand, the bearing members 21 would be exposed to scale dropping from the roll bed were it not for the guards 22 which extend laterally across and beneath the roll bed.

It will be noted that the tilting finger 8^a adjacent the discharge end of the roll bed is preferably U shaped in order to obviate the necessity of supporting that portion of the side guard 2 which extends outside of that tilting finger. The tilting finger, therefore, is preferably formed to extend beneath and around the side guard 2. It will be obvious that the side guard could be divided to provide room for an ordinary tilting finger, if so desired, without departing from the spirit of the invention.

The tilting finger mechanism herein described has certain inherent advantages due to the motor being stationary on the frame of the manipulator, although the tilting fingers are movable transversely of the roll table with the side guard 2. Although no sliding electrical contact is necessary, accurate control of the fingers at all times provided through the squared shaft 16 which is slidable longitudinally in the gear 17. The gear 17 may be rotatably secured in any suitably bearing 17^a attached to the frame supporting the mechanism 7. The pitman 13 controlling the tilting fingers 4 is capable of readily assuming any desired angular position by reason of the ball and socket joint connecting its upper end with the lever 9 and by reason of the forked end engaging a trunnion block 15 rotatable on the pin of the crank 12.

It will be observed that, the shafts S₁—S₂ are indicated as having extension portions S₁' and S₂' by which the manipulator may

be connected up to a corresponding manipulator lying adjacent the device.

Thus I provide an improved manipulator operating mechanism wherein the tilting fingers are movable laterally across the roll bed and are controlled by a motor remaining stationary with respect to the roll bed. Moreover, I provide a manipulator having improved side guard controlling means whereby the side guards are movable selectively across the roll bed.

Further advantages accrued to my invention by reason of the provision of an improved tilting finger operating mechanism comprising a pitman having one end thereof oscillable in a plurality of directions and having the other end constrained to a circular path.

Further advantages arise from the provision of a manipulator having a side guard comprising a plurality of spaced members, and tilting fingers disposed intermediate the spaced members, the tilting fingers being movable laterally with the side guards and being operable by a motor stationary with respect to the frame of the manipulator.

While I have illustrated and described the present preferred embodiment of my invention, it will be understood that it is not limited thereto, but that the invention may be otherwise embodied within the scope of the following claims.

I claim:

1. Means for operating a tilting finger, including a pivoted lever attached to the finger, a pitman engaging the lever, and a crank movable about an axis substantially normal to the axis of the lever pivot for operating the pitman whereby the lever is oscillated about its pivot.

2. Means for operating a tilting finger, including a pivoted lever operatively attached to the finger, a pitman engaging the lever, said pitman having a connection with the lever capable of permitting movement thereof in a plurality of directions relatively to the lever, and a crank for operating the pitman.

3. Means for operating a tilting finger, including a pivoted lever operatively attached to the finger, a pitman engaging the lever, said pitman having a connection with the lever capable of permitting movement thereof in a plurality of directions relatively to the lever, and a crank for operating the pitman, said crank having a crank pin, and means connecting the pitman to the crank pin.

4. Means for operating a tilting finger, including a lever operatively attached to the finger, said lever having a socket associated therewith, a pitman terminating in a ball adapted to cooperate with the socket, a crank pin for moving the pitman, and a means for rotating the crank pin.

5. Means for operating a tilting finger, including a lever operatively attached to the finger, said lever having a socket associated therewith, a pitman terminating in a ball adapted to cooperate with the socket, a crank pin for moving the pitman, and a trunnion block adapted to transmit motion from the crank pin to the pitman, said block being rotatably mounted on the crank pin and having a trunnion thereof engaged by the pitman.

6. Means for operating a tilting finger, including a lever operatively attached to the finger, said lever having a socket associated therewith, a pitman terminating in a ball adapted to cooperate with the socket, a crank pin for moving the pitman, and a means for rotating the crank pin, said means comprising a shaft slidable longitudinally through a pinion, the shaft being of non-circular cross-section and the pinion having an opening substantially conforming with the contour of the shaft.

7. The combination with a manipulator having a stationary frame and a movable side guard with a tilting finger associated with the guard of operating means for the tilting finger, said means including a lever operatively attached to the finger, a pitman engaging the lever, a crank for operating the pitman, a shaft for rotating the crank, the shaft being slidable longitudinally through a pinion and having a non-circular cross-section substantially conforming with a cooperating opening in the pinion, said pinion being operable by a motor stationary with respect to the frame, the cross-section of the shaft being uniform whereby the shaft is slidable through the pinion without effecting rotation.

8. The combination with a manipulator having a stationary frame and a movable side guard having a plurality of tilting fingers associated therewith, of operating means for the tilting fingers, said means including a plurality of levers to which the fingers are attached, said levers being mounted on rotatable means controlled by a common rotating mechanism, the rotating mechanism comprising a lever attached to the rotatable means, said lever having a socket thereon, a pitman terminating in a ball adapted to cooperate with said socket, means movable in a substantially circular path for operating the pitman, and connecting means attaching the pitman operating means to the pitman.

9. The combination with a manipulator having a stationary frame and a movable side guard having a plurality of tilting fingers associated therewith, of operating means for the tilting fingers, said means including a plurality of levers to which the fingers are attached, said levers being mounted on rotatable means controlled by a common rotating mechanism, the rotating mechanism

comprising a lever attached to the rotatable means, said lever having a socket thereon, a crank pin for operating the pitman, and connecting means attaching the crank pin to the pitman, said means comprising a trunnion block rotatable on the crank pin, the trunnions of said block being engaged by the pitman.

10. A manipulator including a lever, a tilting finger carried thereby, means operable in a plane at an angle to the plane of the lever and below the same for operating the same, and a universal connection between the operating means and the lever.

11. A manipulator including a lever, a tilting finger carried thereby, means operable in a plane at an angle to the plane of the lever for operating the same, and a pitman connecting the operating means and the lever, each end of the pitman having a universal connection.

12. A manipulator including a lever, a tilting finger carried thereby, operating means movable in a plane at an angle to the plane of the lever, a pitman connecting the operating means and the lever, and a ball and socket joint connecting the pitman and the lever, the pitman having a universal connection with the operating means.

13. A manipulator including a lever, a plurality of tilting fingers, means connecting the tilting fingers, said means being operable by the lever, means movable in a plane at an angle to the plane of the lever for operating the same, a pitman connecting the operating means and the lever, and a ball and socket joint connecting pitman and the lever, the other end of the pitman having a universal connection with the operating means.

14. Means for operating a tilting finger, including a lever operatively attached to the finger adjacent one end and having a pivotal mounting adjacent its opposite end, a pitman having a universal connection with the lever intermediate its ends, and means for operating the pitman.

15. Means for operating a tilting finger, including a lever operatively attached to the finger adjacent one end and having a pivotal mounting adjacent its opposite end, a pitman having a universal connection with the lever intermediate its ends, and means for operating the pitman, said means comprising a crank located below the lever.

16. Means for operating a tilting finger, including a lever operatively attached to the finger adjacent one end and having a pivotal mounting adjacent its opposite end, a pitman having a universal connection with the lever intermediate its ends, and means for operating the pitman, said means comprising a crank located below the lever, and having its axis of rotation substantially normal to said pivotal mounting.

17. Means for operating a tilting finger,

including a pivoted lever operatively attached to the finger, a pitman having universal connection with said lever, and a crank for operating the pitman, said crank lying below said lever.

18. Means for operating a tilting finger, including a lever operatively attached to the finger adjacent one end, said lever having a socket associated with an intermediate portion thereof, a pitman terminating in a ball adapted to cooperate with the socket, and a crank for effecting movement of said pitman.

19. Means for operating a tilting finger, including a lever, a crank below the lever, and a universal operating connection between the crank and lever.

In testimony whereof I have hereunto set my hand.

JOHN A. SMITMANS.
